Attorney.

UNITED STATES PATENT OFFICE.

LAWRENCE L. BROWNE, OF KANSAS CITY, KANSAS.

WEATHER STRIP.

Application filed April 3, 1925. Serial No. 20,477.

My invention relates to improvements in weather strips and my object is to provide devices of this character from resilient metal cut into suitable lengths for attachment to window frames, window sash, doors and door frames for the purpose of excluding air currents, snow, rain, dust, etc.

A further object is to provide a weather strip with double bearing surfaces for engagement with window sash or doors for the purpose of preventing rattling thereof and effectively sealing the space between said sash or doors and their respective frames, said weather strip being so constructed as to be easily applied without the necessity of removing the sash or doors.

In order that the invention may be fully understood, reference will now be had to the accompanying drawing, in which:

Fig. 1 is a broken perspective view partly in section of the lower portion of a window frame equipped with the weather strip.

Fig. 2 is a broken vertical section of upper and lower sashes with the meeting rail of the upper sash equipped with the weather strip.

Fig. 3 is a broken horizontal section of a window frame and sash with the latter equipped with the weather strip.

Fig. 4 is a broken horizontal cross section of a window frame and sash with the former equipped with the weather strip.

Fig. 5 is a broken perspective view of a portion of the weather strip.

Referring in detail to the different parts disclosed by the drawing, A designates a window frame provided with the usual stop B; C the window sill surmounted by the usual stool D; and F and G the meeting rails of the upper and lower sash E and H, respectively.

As shown more clearly by Fig. 5, the weather strip 2 is bent at an acute angle 3 longitudinally along approximately its central portion to form two longitudinal leaves 4 and 6 having longitudinal wings 8 and 10 extending at substantially right angles thereto. The strip 2 consists preferably of non-corrodible metal such as bronze and is of the usual length of stock material of this class.

In Fig. 1 the wing 8 is slipped between the window sill C and the stool D, to which latter the weather strip 2 is secured by suitable means such as tacks L, which are driven

through the folded portion near the acute angle 3 of said weather strip 2. When the sash H is lowered the weather strip 2 will have a double bearing surface thereon through the intermediacy of the leaf 6 and the wing 10, which seal the intervening space and prevent rattling of said sash H by urging the same against the parting strip K.

Fig. 2 shows the leaf 4 secured to the inner face of the meeting rail F of the upper sash E and wing 8 bearing against the underface of said meeting rail, with the leaf 6 and the wing 10 arranged in the path of the meeting rail G of the lower sash H, so that when the same is closed the weather strip 2 will have a double bearing surface on said meeting rail G.

Fig. 3 shows the wing 10 tacked to the adjacent stile of the upper window sash E, and the leaf 4 and the wing 8 bearing against the blind stop M.

In applying the weather strip 2 to the window frame A, as disclosed by Fig. 4, the vertical stop B is removed so that the wing 8 may be secured to said frame by suitable means such as tacks J in such position that when the stop B is replaced the face of the leaf 4 will bear against the adjacent margin of said stop B while the leaf 6 and the wing 10 will bear against the lower sash H and thus provide a double bearing surface between the weather strip 2 and said sash.

When the weather strip 2 is applied as stated, the resiliency of the leaf 6 and the wing 10 serves to urge the sash H against the adjacent face of the parting strip K and thus effectively seal the intervening space and prevent said sash H from rattling.

Another desirable feature of my weather strip resides in the fact that only a small amount of space is required to install and firmly hold it in place.

While I have shown the preferred form of my weather strip, I reserve the right to such changes and modifications thereof as properly fall within the spirit and scope of the invention as claimed.

Having thus described my invention, what I claim and desire to secure by Letters Patent, is:

A weather strip consisting of a length of resilient metal folded longitudinally along its intermediate portion for forming two longitudinal leaves tending to spring apart

and attachable to the lower inner margin of an upper sash, a longitudinal wing formed integral with one of said leaves and extending approximately at right angles therefrom to abut the bottom surface of said sash, and a longitudinal wing formed integral with and extending approximately at right angles

to the other leaf and adapted to coact therewith in forming a double contact with the upper meeting rail of the lower sash when ¹⁰ the sash are closed.

In testimony whereof I affix my signature.

LAWRENCE L. BROWNE.
